DISPENSING DEVICE

Leif Nelson Booger, Brooklyn, N. Y.

Application March 6, 1937, Serial No. 129,510

5. Claims. (Cl. 221—66)

This invention relates to a dispensing or discharge control device for containers.

The device may be used advantageously for controlling the discharge of granular material such as dental and talcum powder.

An object of the invention is the provision of a device of the indicated character which requires agitation of a container contents in order to discharge a desired quantity therefrom.

10 A further object of the invention is the provision of a device of the indicated character which prevents the unintentional discharge of any of the contents of a container when the latter is disposed in a discharging position.

15 A further object of the invention is the provision of a simple and inexpensive device of the indicated character, and one which is of effectual and substantial design.

With the foregoing other objects of the invention will appear from the embodiment thereof, which by way of example is illustrated in the accompanying drawing, described in the following specification, and defined as to scope in the appended claims.

25 In the drawing:

Fig. 1 is a perspective view of a container selected to illustrate the device of the present invention applied thereto.

Fig. 2 is a side view and part section of the container disposed in a discharging position and illustrating the manner in which the device operates for the purpose of discharging some of the contents from the container.

Fig. 3 is a section taken approximately on the line 3—3 of Fig. 2; and

Fig. 4 is a perspective view of the rotor which constitutes the agitating means of the device.

Referring now more particularly to the several views of the drawing, it will be apparent, that the device of the present invention is shown in conjunction with a container consisting in the present instance of a body 10 and a cap 11 applied to the outlet end of said body 10. As shown, the cap 11 conforms to and fits the outlet end of the body 10. In the present instance the cap consists of a wide portion 12 which merges into a relatively restricted portion 13. The wide portion 12 fits the outlet end of the body 10. The restricted portion 13 embodies substantially parallel side walls 14 and an arcuate wall 15 between the walls 14 and joining the latter.

In accordance with the invention, the arcuate wall 15 of the cap 11 is provided with a series of discharge apertures or ducts or openings 16, and the same may be formed in any suitable manner

so as to impede the flow of the material to be discharged, and requires additional means which may be manipulated to positively cause the discharge of the desired quantity of the material from within the cap thru said apertures or ducts or openings. To this end, the apertures etc. are outwardly restricted, and this is accomplished in the present instance by the material of the cap being directed inwardly as indicated at 17 in Fig. 2.

10 In order to positively dispense or discharge a desired quantity of the contents of the container thru the restricted apertures etc., there is provided an agitating means in the form of a rotor 18. This rotor 18 is carried by the cap 11. The 15 rotor 18 includes an arbor 19 which is supported by the side walls of the portion 12 of the cap 11. It is to be understood that the arc of the wall 15 is struck from the axis provided by the arbor 19. The rotor is constructed to provide radial members 20 on the arbor 19, said members having flexible extremities 21 of rubber or any other suitable flexible material which are adapted to come in wiping contact with the arcuate wall 15 as indicated most clearly in Fig. 2. The extremities 21 serve for the purpose of positively causing the powder to be discharged from within the cap thru the ducts 16 when the container is disposed in an inverted or discharging position and while the rotor 18 is being rotated. As stated, the ducts 20 16 are so formed as to impede the flow of material or powder and require the wiping action of the rotor 18 in order to discharge the desired quantity of the material or powder. If desired, the rotor 18 may be provided with laterally extending wings 22 on the members 20 respectively. These wings 22 augment the action of the flexible extremities 21 in agitating the contents so as to obtain an easy flow thereof and to prevent clogging or compacting of the contents. In order to rotate the rotor 18, the arbor 19 is provided with a knurled knob 23 which is exposed exteriorly of the cap 11. By manipulating the knob 23 the rotor 18 may be readily rotated for the intended purposes.

40 The rotor 18 may be prevented from having axial movement by any suitable means such as the burrs 24 pinched from the material of the arbor 19.

The cap 11 is provided with shoulders 25 to 50 accommodate a closure 26 which may be slid endwise into position to seal the ducts 16, said closure also having openings for slots to coincide with the ducts 16 of the cap 11 and which may be moved endwise and set so as to regulate, 55

adjust or further impede the flow of material thru the ducts 16.

It is to be understood that the invention is not restricted to the precise construction illustrated but that details of construction may be modified and rearranged without departing from the spirit of the invention as defined in the claims.

What is claimed as new and useful is:

1. The combination with a container having a series of discharge openings, of a rotor within said container, said rotor having flexible agitating portions, and means connected with said rotor and disposed exteriorly of the container to operate the rotor to cause said flexible portions to act on the contents of the container and thus discharge a desired quantity of the contents through said openings.

2. The combination with a container having an arcuate wall, said wall having a series of discharge openings, of a rotor within said container, said rotor having radial flexible wiping portions, and means connected with said rotor and disposed exteriorly of the container to operate the rotor to cause said flexible portions to act on the contents of the container and thus discharge a desired quantity of the contents through said openings.

3. The combination with a container having a series of discharge openings, of a rotor within

said container, said rotor having radial members terminating in flexible agitating portions, and means connected with said rotor and disposed exteriorly of the container to operate the rotor to cause said flexible portions to act on the contents of the container and thus discharge a desired quantity of the contents through said openings.

4. In a device for dispensing granular material, a container for the material, said container having a multiplicity of outwardly restricted discharge ducts and means operable exteriorly of the container including an essentially flexible rotatable paddle-like member abutting against the inner parts of said ducts which acts on said material to positively eject desired quantities of the material from the container through said ducts.

5. In a device for dispensing powdered material, a container for the material, said container embodying an arcuate wall having a series of outwardly restricted discharge ducts, and a rotor supported by certain walls of the container to operate within the latter, said rotor having flexible wipers which move with respect to said arcuate wall and act on said material to dispense desired quantities of the material from the container through said ducts.

LEIF NELSON BOOGER.
